UNITED STATES PATENT OFFICE.

JOHN GILLELAND, OF ATHENS, GEORGIA.

IMPROVED MODE OF BLASTING ROCKS.

Specification forming part of Letters Patent No. 30,809, dated December 4, 1860.

To all whom it may concern:

Be it known that I, JOHN GILLELAND, of Athens, in the county of Clark and State of Georgia, have invented a new and useful Improvement in Blasting Rocks; and I do hereby declare that the following is a full, clear, and exact description of the same, reference being had to the annexed drawing, said drawing being a vertical section of a rock drilled and charged according to my invention.

The object of this invention is to prevent accidents, which frequently occur in blasting rocks, owing to the tamping of the wadding over the charge of powder in the hole, the metal rod necessarily employed for the purpose in coming in contact with the side of the hole developing sparks of fire which cause the ignition of the powder.

The invention consists in having the hole which is drilled in the rock to receive the charge of two different diameters, the lower part of the hole, which receives the powder, being smaller in diameter than the upper part, which receives the wadding, and using a division-plate and spindle applied and arranged in the hole substantially as herein-after described, whereby the wadding may be placed in the hole and tamped before the insertion of the powder, and all accidents avoided.

To enable those skilled in the art to fully understand and practice my invention, I will proceed to describe it.

A represents a rock, and B B' B'' holes drilled in it to receive charges for blasting it. These holes, it will be seen, are each of two different diameters, the upper parts, *a*, being somewhat larger than the lower parts, *b*, drills varying from a quarter to a half-inch in size being used, the larger drill first, and then the smaller one. The lower parts, *b*, of the holes are made sufficiently deep to receive the necessary charge of powder, and the upper parts, *a*, are drilled sufficiently deep to receive a requisite amount of wadding to properly confine the powder. After the holes are drilled and properly cleaned out, a plate, C, of metal or other suitable substance, is placed in the holes, said plates resting on the shoulders *c*, which are formed by the differ-

ence in the diameters of the two parts *a b* of the holes. The plates C are tapped at their centers to receive the lower ends of spindles D, which are screwed into the plates. The parts *a* of the holes are then filled with wadding *d*, the latter being firmly tamped or rammed down, so as to prevent being blown out. The spindles D are then unscrewed from the plates C and withdrawn, and a hole, *d'*, will consequently be at the center of the wadding in each hole in the rock, (see hole B'), and a funnel, E, is placed in the orifices of the holes *d'*, and the lower parts, *b*, of the holes are charged with powder *e*. A fuse, *f*, may then be inserted in each hole *d*, and the charge ignited as usual. By this arrangement it will be seen that no accident can possibly occur in tamping or ramming down the wadding, for such work is done before the powder is inserted in the hole, and the wadding can therefore be rammed down with great force, so as to effectually prevent the contingency of its being blown out. There is another advantage attending this invention, and that is the lower parts, *b*, of the hole may be made sufficiently deep to allow a space above the powder, between it and the plate C, to admit of the expanding of the gases when the powder is ignited, and thereby enabling the latter to act more efficiently than it otherwise would.

The invention is an extremely simple as well as useful one, and will not add in an appreciable degree to the usual cost of blasting rocks.

I would remark that the screws at the ends of the spindles may be dispensed with, and the spindle merely fitted in the plates.

Having thus described my invention, what I claim as new, and desire to secure by Letters Patent, is—

Blasting rocks by having the hole which receives the charge of two different diameters, the smaller one, *b*, to receive the powder, and the larger one, *a*, to receive the wadding, and using in connection therewith a plate, C, and spindle D, respectively applied and manipulated substantially as set forth.

JOHN GILLELAND.
